United States Patent Office

Des. 218,915
Patented Oct. 6, 1970

218,915

KAYAK

Frederick M. Getzschman, Jr., 4829 Holmes St., Apt. 218
68117, and David Getzschman, 1367 S. 76th Ave.,
Apt. 20 68124, both of Omaha, Nebr.

Filed June 12, 1969, Ser. No. 17,672

Term of patent 14 years

Int. Cl. D12—06

U.S. Cl. D71—1

FIG. 1 is a top view of the kayak;
FIG. 2 is a side elevational view of the kayak;
FIG. 3 is a front elevational view of the kayak;
FIG. 4 is a back elevational view of the kayak;
FIG. 5 is a bottom view of the kayak; and
FIG. 6 is a top view of a modified form of the kayak illustrating a storage compartment provided therein.

We claim:

The ornamental design for a kayak, substantially as described and shown.
